[57] CLAIM

The ornamental design for a plant hanger, as shown and described.

DESCRIPTION

FIG. 1 is a top perspective view of a plant hanger showing my new design, shown broken away to indicate indeterminate length;

FIG. 2 is a bottom perspective view thereof;

FIG. 3 is a top perspective view of a second embodiment of the design of FIG. 1;

FIG. 4 is a bottom perspective view of FIG. 3;

FIG. 5 is a top perspective view of a third embodiment of the design of FIG. 1;

FIG. 6 is a bottom perspective view of FIG. 5;

FIG. 7 is a top perspective view of a fourth embodiment of the design of FIG. 1;

FIG. 8 is a bottom perspective view of FIG. 7.

The broken lines in FIGS. 1, 3, 5 and 7 are for illustrative purposes only.

FIG. 4

FIG. 3
